UNITED STATES PATENT OFFICE.

ROBERT W. HARE, OF PITTSBURG, PENNSYLVANIA.

LOCKING DEVICE FOR ELEVATORS.

SPECIFICATION forming part of Letters Patent No. 687,306, dated November 26, 1901.

Application filed March 18, 1901. Serial No. 51,654. (No model.)

To all whom it may concern:

Be it known that I, ROBERT W. HARE, a citizen of the United States, residing at Pittsburgh, in the county of Allegheny and State of Pennsylvania, have invented new and useful Improvements in Locking Devices for Elevators, of which the following is a specification.

My invention relates to improvements in locking devices for elevators, and pertains to means whereby the controlling member for the elevator-power is locked when one or more of the doors in the elevator-shaft is open, all of which will be fully described hereinafter.

The object of my present invention is to provide means for locking the elevator-power controller when one of the doors of the elevator-shaft is open, whereby the elevator-car cannot be moved while the door is open, and to lock the door closed when it is shut, and at the same time to release the elevator-power controller, whereby the attendant can cause the movement of the elevator-car in either direction in the elevator-shaft when the door is closed.

My present invention is so constructed that the door cannot be moved at all in the direction of opening it until the elevator-power controller is positively and absolutely locked, and the construction is such that the door is locked closed absolutely before or at the same time that the elevator-power controller is released and before the car can be moved.

In the accompanying drawings, Figure 1 is a side elevation of an elevator-well, the doors being shown shut and the controller-locking device released. Fig. 2 is a similar view, the lower door being open and the locking device positively locking the elevator-controller. Fig. 3 is an enlarged view of that part of my locking mechanism that cooperates with the door for locking and releasing it. Fig. 4 is a detached perspective view of the sheave or wheel around which the elevator-controller rope passes and the locking-latch, which is adapted to lock and release the said sheave, according to whether the doors in the elevator-shaft are closed or one of them is open. Fig. 5 is a detached enlarged perspective view of the door-locking latch and the handle or lever by means of which it is actuated.

The general construction of an elevator-well and the sliding doors is so well understood by

those skilled in the art that any particular description thereof is unnecessary, and they will therefore only be referred to briefly in a general way and specifically in those details which pertain to my present invention.

A is the elevator-well framework, and B the sliding doors, which are adapted to be moved into closed and open positions for the purpose of permitting access to and preventing exit from the elevator-car. These doors and the elevator-well may be of the ordinary construction, as they themselves form no part of my present invention.

C is the sheave, around which the usual elevator-controlling rope D passes, and the wheel C, as is well understood by those skilled in the art, is adapted to control the elevator-power, whether that be electrical, hydraulic, or other power. This sheave or controller-wheel C is provided with one or more projections a, which form a locking-notch for the engagement of one end of the locking-lever E. The locking end d is heavier than the opposite end of the lever E, whereby the locking-lever is normally in the position shown in Fig. 2, and therefore normally in engagement with the controller sheave or wheel C. This locking-lever E is controlled through the means of the mechanism which I will now describe.

The mechanism which I use for controlling this locking-lever E is adapted to be modified in many ways without departing from the spirit and scope of my present invention, the preferred form, on account of simplicity and cheapness in construction, being that shown in the accompanying drawings. This mechanism consists of a lever F for each door, and which has one end pivotally connected, as shown at e, its opposite and free end adapted to pass through a suitable slotted keeper G, which is attached to the inner side of the door near its edge. This lever F has its free end provided with a vertically or laterally arranged shoulder f, which is adapted to engage with the said slotted keeper G when the door is closed, as shown in Fig. 3, and thus positively and absolutely lock the door closed until the free end of the said lever F is lifted for the purpose of carrying the shoulder f in a line with the slot or opening h in the said keeper. For the purpose of forming a support for the inner end of the said lever F, I

provide the door with an angle-iron or bracket H, which extends transverse the door and is attached to its inner side. Any desired means may be provided for lifting the said lever F, or 5 it may be lifted directly; but, as here shown, I prefer to use an intermediately-pivoted lever I, carried by the door B, which has one end *i* adapted to engage the free end of the lever F and its opposite end *j* formed into a 10 handle by means of which it can be depressed and the free end of the lever F raised for the purpose of permitting the door B to be opened. 15 A rope, chain, or other ligament J is suitably adapted to engage with the free end of the lever F. As here shown, the manner of 20 making this engagement consists in providing the free end of the lever with the laterally-projecting ear K, said ear having a perforation *m*, through which the said rope or 25 ligament J is adapted to pass. The rope or ligament J is provided with a suitable stop M, which is preferably adjustably connected therewith for the purpose of resting or engaging the upper side of the said ear K of the 30 lever F. This rope or ligament preferably passes around a sheave or pulley N at the upper end of the elevator-well and carries a weight P, and its lower end passes through an opening *r'*, made in the end *r* of the said 35 locking-lever E. The ligament or rope J is also provided with a stop *s*, adapted to engage the upper side of the lever, as shown in Fig. 1, for the purpose of depressing the said lever and moving its opposite end upward in 40 position (shown in said Fig. 1) for releasing the said controller-pulley C. Connected to the lower end of the rope or ligament J is a weight S, which is heavier than the weight P and normally holds the rope or ligament down, as 45 shown in Fig. 1, and consequently normally holds the locking-lever E in its unlocking position.

In operation when the attendant of the elevator reaches a floor in the building and 45 wishes to open the door B he depresses the end *j* of the lever I, which moves the free end of the lever F upward and pushes its shoulder *f* out of engagement with the keeper G upon the door. This movement lifts the ligament 50 or rope J and permits the lever E to assume the position shown in Fig. 2, and in this position it locks the controller-wheel C. It will thus be noted that this movement accomplishes a two-fold function—namely, the locking 55 of the controller-wheel C and the unlocking of the door B. It will also be noted that the controller-wheel C is locked before the door can be moved, or, in other words, is locked before the door is unlocked. This 60 will absolutely prevent any accidents in the use of a device having these characteristics.

When the door B is closed, the lever F falls to the position shown in Fig. 1, and the weight S draws the ligament or rope J downward, thus releasing the locking-lever E of the controller C. Here it will be noted that the door is locked before the locking wheel or sheave C is released, which insures absolutely not only the closing of the door, but the locking of the door, before the controlling means is 65 released, and hence the locking of the door before the elevator can be moved.

It will be readily understood that many modifications of this specific construction could be devised for the purpose of accomplishing the ends and operation hereinbefore set forth.

Having thus described my invention, what I claim, and desire to secure by Letters Patent, is—

1. In an elevator, an elevator-well, a longitudinally-sliding door therefor, said door having at a point intermediate its ends a locking-lever slideway and support, a hand-operated horizontal lever pivoted at one end to said well and having its opposite end adapted to rest upon said slideway, a motor-controller, a lock therefor, and a controlling-line for said lock having a shoulder in the line of travel of the free portion of said pivoted lever. 90

2. In an elevator, an elevator-well, a sliding door therefor, a horizontal locking-lever having one end pivoted to said well, a locking and lever-supporting member carried by said door, a hand-lever-actuating member carried by the door for lifting the free locking end of the horizontal lever, and a motor-controlling line having a shoulder in the line of travel of the free end of said locking-lever. 95

3. In an elevator, a motor-controlling line, 100 a motor-controlling device between the line and the motor, a lock for said device, a hand-operated lever having a vertical opening in its free end, and a line controlling said lock passing loosely through said opening and provided with a shoulder in the path of the free 105 end of said lever.

4. In an elevator, a motor-controlling line, a motor-controlling device between the line and the motor, a lock for said device, a line 110 controlling said lock, and a lever having one end pivotally supported and its opposite free end constituting a combined hand and lock line operating end.

In testimony whereof I have hereunto set 115 my hand in the presence of two subscribing witnesses.

ROBERT W. HARE.
